United States Patent Office.

ANDREW HARTMAN, OF CANTON, OHIO.

Letters Patent No. 64,764, dated May 14, 1867; antedated May 5, 1867.

IMPROVED RAILROAD SWITCH.

The Schedule referred to in these Letters Patent and making part of the same.

TO ALL WHOM IT MAY CONCERN:

Be it known that I, ANDREW HARTMAN, of Canton, in the county of Stark, and State of Ohio, have invented certain new and useful Improvements in Railroad Switches; and do hereby declare that the following is a full, clear, and exact description thereof, reference being had to the accompanying drawings, and to the letters of reference marked thereon, making a part of this specification.

Figure 1 represents a plan view of the railroad switch.

Figure 2, a section of the same through line $z z$, fig. 1.

Figure 3, a side view with the car and device attached thereto for operating the switch.

In the annexed drawings, A represents the main track, which is connected by a bar, a , near the switch. B B are the rails of the side track, and stationary, while the rails A A of main track are movable. At one side of the track, and about one rail's length apart each side of the switch, are L-shaped levers, which are pivoted to a board or plate at the point where they are bent, and so placed that when in their natural positions the longest end lies directly against the main track at one end, D, and the side track at the other, D'. E represents a triangular-shaped plate, lying about one half way between the two levers D D', and which is pivoted at z . Extending from the outer and inner points of this plate are rods $d d$, which connect to the outer ends of levers D and D' respectively. The other point is connected to the rail by means of a rod, W, and readily draws the track back or forth when the levers are operated. b is a curved metal bar, which lies between the rails A A, and, by means of prongs and small openings in the track, passes through it at both sides. At the side opposite the levers, and suspended under the bar b, is a weight, m, pivoted to and attached to a trigger, n, which extends just beyond the rail, and between the prongs of the bar b. Suspended from said bar, slightly beyond the weight m, is a tumbler, g, which is operated by means of a rod, o, connected to the opposite rail. S represents a coil spring placed within a metal case near the plate E at the outside of the rails, so that when the track is drawn from the main to the sideling, and not held there, the aforesaid spring will recoil and force the track to its natural place.

It will be observed that whenever the track is drawn to the sideling, that rod o turns the tumbler g, thereby releasing the weight m, which falls and causes the trigger n to come up and secure the track. Pivoted to the outside of the track is an eccentric, C, which is just over the end of the trigger, and which is operated by the locomotive. F represents a car, showing the devices which are connected to the locomotive and hindmost car for operating the switch. The attachment for the locomotive is shown at l, which is a hand upright lever which elevates a rod or lowers it, which is connected to an L-shaped bar for raising or lowering a shoe, q. When nearing the switch the shoe is lowered, and forces the eccentric upon and operates the trigger, causing the switching of the rails.

Having thus fully described my invention, what I claim as new, and desire to secure by Letters Patent, is—

In an automatic switch the arrangement of the plate b with tumbler g, at m, trigger n, and spring s, operated by the shoe q and eccentric C, connected to the railroad car and , respectively, when used in combination with the plate E, levers D D', (connected by the rods d,) and operating in the manner substantially as specified.

As evidence that I claim the foregoing I have hereunto set my hand in the presence of two witnesses.

ANDREW HARTMAN.
